(57) **CLAIM**

The ornamental design for an earphone with charging case, as shown and described.

DESCRIPTION

FIG. 1 is a front, left and top perspective view of the earphone of the earphone with charging case, showing my new design, shown separately for ease of illustration;

FIG. 2 is a rear, right and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and

FIG. 8 is a bottom plan view thereof;

FIG. 9 is a front, left and top perspective view of the charging case of the earphone with charging case, shown separately for ease of illustration;

FIG. 10 is a rear, right and bottom perspective view thereof;

FIG. 11 is a front view thereof;

FIG. 12 is a rear view thereof;

FIG. 13 is a left side view thereof;

FIG. 14 is a right side view thereof;

FIG. 15 is a top plan view thereof;

FIG. 16 is a bottom plan view thereof; and

FIG. 17 is an enlarged view of portion of FIG. 10 thereof; and,

FIG. 18 is a perspective view of the earphone with charging case.

The broken line showing of the earphone in FIG. 18 is for the purpose of illustrating environment and forms no part of the claimed design. The dot-dash broken lines shown in FIG. 10 and illustrated in FIG. 17 depict the boundaries of the enlarged view and form no part of the claimed design. All other broken lines shown in the drawings illustrate portions of the earphone with charging case that form no part of the claimed design.

1 Claim, 18 Drawing Sheets
